UNITED STATES PATENT OFFICE.

CHARLIE W. SCOTT, OF LINCOLNTON, GEORGIA.

INTERNAL-COMBUSTION ENGINE.

Application filed February 14, 1925. Serial No. 9,210.

To all whom it may concern:

Be it known that I, CHARLIE W. SCOTT, a citizen of the United States, residing at Lincolnton, in the county of Lincoln and State of Georgia, have invented certain new and useful Improvements in an Internal-Combustion Engine, of which the following is a specification.

This invention relates to an improved internal combustion engine, having particular reference to a multiple cylinder and piston structure with which novel power transmission means is associated.

The ordinary internal combustion engine, such as is used in automobiles, embodies an arrangement of multiple cylinders and pistons reciprocable therein, together with a single crank shaft and connecting rod between the pistons and cranks.

It has been observed from time to time that in this well known arrangement of parts, an undesirable degree of friction is generated between the pistons and cylinders, and owing to the uneven wear of the pistons against the cylinder walls, leakage, loss of compression and other disadvantages result.

I aim to improve upon the arrangement briefly described by providing a dual arrangement of crank shafts intergeared for simultaneous rotation in opposite directions for supplying power to the propeller shaft, the cranks of this shaft being connected with the reciprocating piston by pairs of independent connecting rods.

The foregoing constitutes the principal feature of the invention, but an important advantage is derived from the use of wear resisting pistons, the pistons in the present instance being such in construction that true rectilinear reciprocation is assured at all times.

Other features, advantages, and structural differences over the common engine structure will become apparent from the following description and drawing.

In the accompanying drawing forming a part of this application and in which like numerals are employed to designate like parts throughout the same:

Figure 1 is a central vertical longitudinal section through an internal combustion engine constructed in accordance with the present invention, portions being shown in elevation.

Fig. 2 is a vertical transverse section

taken approximately on the plane of the line 2—2 of Fig. 1.

Referring to the drawing in detail, the reference character 1 indicates generally the improved cylinder head which, as is customary, is provided with an appropriate water circulating jacket 2 for cooling purposes.

Associated with the bottom of the cylinder head is a crank case 3, the configuration of which is such as to accommodate rotation of the oppositely moving crank shafts 4 and 5 respectively. At their forward ends, these crank shafts are geared together by intermeshing gears 6. The gears rotate in the direction obvious from Fig. 2. As stated, the cylinder head embodies a plurality of cylinders 7 in which piston heads 8 are slideable.

Inasmuch as each cylinder and piston together with its connection with the crank shafts is the same, the description will now appear in the singular, it being understood that all like reference characters designate like parts.

Directing attention to Fig. 2 it will be seen that the piston head 8 is provided with an internal cross pin 9 with which a substantially flat stem 10 has pivotal connection. The stem extends downwardly into the elongated portion of the cylinder and is provided with spaced parallel arms 11 which are in turn provided at their lower ends with substantially semi-circular arcuate shoes 12. The adjacent ends of the shoes are spaced apart and opposite these spaced ends are vertical slots 13 formed in the lower extended end of the cylinder.

As seen in the figure referred to the extended slotted end of the cylinder extends down into the crank case 3. Extending through the arms 11 outward of the shoes 12 is a cross pin 14 to which a substantially triangular connector 15 is connected. This connector is provided with appropriate bearings, one of which is connected with the pin as stated and the other two of which are connected with the upper ends of duplicate connecting rods 16 and 17.

The connecting rods are connected at their lower ends to the cranks of the aforesaid crank shafts 4 and 5. The connecting rods work through the slots 13. If desired, a reinforcing spider 18 may extend crosswise of and be connected to the arcuate shoes 12.

As the piston is driven downwardly under the action of the explosion, the connecting rods 16 and 17 serve to rotate the crank shafts 4 and 5 in opposite directions and to impart corresponding rotation to the intermeshing gears 6. The proper angling of the connecting rod is permitted by the triangular connector 15 between the rockable stem of the piston and the pin 14 10 with which it is connected.

It is thought that an engine constructed in accordance with the description and drawing will serve to decidedly increase the degree of power and will insure a more 15 continuous rotation of the propeller shaft. Under the construction specified, it is thought that greater power will be derived, undue heating will be eliminated owing to the diminished friction, and an altogether 20 more efficient operation will be insured.

These and other features and advantages of the invention have doubtless been made apparent by the foregoing description and the accompanying drawing. For this reason, it is thought that a more lengthy 25 description is unessential.

Although the preferred embodiment of the invention has been shown and specifically described, it is to be understood that 30 changes coming within the field of the invention claimed may be resorted to if desired.

Having thus described my invention, what I claim as new is:—

1. In an engine structure of the type specified, an elongated cylinder the wall of which is provided at its lower end with diametrically opposite slots opening through the bottom, a piston slideable in said cylinder, a connecting rod pin carried by said piston, a stem connected to said pin, spaced arms depending from said stem and provided at their lower ends with substantially arcuate shoes in slideable contact with the opposed walls of the cylinder, a triangular connector connected with said arms, connecting rods connected with said connector, and intergeared simultaneously operated crank shafts with which the lower ends of said connecting rods are connected.

2. As a new article of manufacture, a piston and connecting rod structure for use in conjunction with an elongated cylinder, said structure comprising a piston head, a 55 cross pin located therein, a stem depending from and pivotally connected to said pin, a pair of arms carried by said stem, and arcuate shoes on the lower end of said arm, said shoes being disposed in diametrically opposed relation with their ends spaced apart. 60

In testimony whereof I affix my signature.

CHARLIE W. SCOTT.
